UNITED STATES PATENT OFFICE

150,568

DESIGN FOR AN INFANT'S SHOE

Steve Griffin, Alameda, Calif.

Application May 3, 1948, Serial No. 146,153

Term of patent 14 years

(Cl. D7—7)

To all whom it may concern:

Be it known that I, Steve Griffin, a citizen of the United States, residing in the county of Alameda, State of California, have invented a new, original, and ornamental Design for an Infant's Shoe, of which the following is a specification, reference being had to the accompanying drawings, forming a part thereof.

Fig. 1 is a perspective view of an infant's shoe, showing my new design.

Fig. 2 is a top perspective view of the shoe.
I claim:

The ornamental design for an infant's shoe, as shown.

STEVE GRIFFIN.
